UNITED STATES PATENT OFFICE.

FREDERICK KIEKENAPP, OF FARIBAULT, MINNESOTA.

SUPPLEMENTAL POCKET FOR POOL AND BILLIARD TABLES.

SPECIFICATION forming part of Letters Patent No. 281,518, dated July 17, 1883.

Application filed April 19, 1883. (No model.)

To all whom it may concern:

Be it known that I, FREDERICK KIEKENAPP, of Faribault, in the county of Rice and State of Minnesota, have invented a new and Improved Supplemental Pocket for Pool and Billiard Tables; and I do hereby declare the following to be a full, clear, and exact description of the same, reference being had to the accompanying drawings, forming a part of this specification, and to the figures and letters of reference marked thereon.

My invention has for its object to provide a protective lining for the ordinary open work or knitted pockets of pool and billiard tables, whereby the knitted pockets are rendered durable and capable of lasting as long as the other parts of the table.

To this end it consists in the provision of a supplementary pocket, of leather, paper, rubber, or other suitable equivalent flexible material, adapted to be inserted into the ordinary knitted pocket of a table, having its upper portion cut away at its front for the admission of the ball, and extended at its back so as to project above the level of the table and receive the impact of the ball; and it further consists in forming upwardly-extending flexible fingers at the front cut-away portion of such supplementary pocket, which fingers are adapted to be tacked or otherwise fastened to the table, and, while they do not project up so as to interfere with the ready entrance of the ball into the pocket, protect the front portion of the knitted pocket from contact with the ball.

In the accompanying drawings, Figure 1 represents a perspective view of a supplemental pocket constructed in accordance with my invention. Fig. 2 is a longitudinal sectional view, and Fig. 3 is a top plan view of the same.

Similar letters of reference in the several figures indicate the same parts.

A represents a supplemental pocket, constructed preferably of leather, molded or pressed into the shape shown, the parts being united by a central seam, *a*, extending down the front side and across the bottom, as shown. The upper front portion of the pocket A is

cut away, and the material of the pocket at that point is slitted, so as to form a series of 50 outwardly-flaring fingers, B, while the rear portion, C, remains intact, and is extended up above the end of the fingers B, being preferably pressed so as to flare slightly backward, as shown clearly in Fig. 2. One or 55 more openings, D, are preferably formed in the bottom to permit the exit of any dirt, dust, chalk, &c., that may fall into the pocket.

In applying this supplemental pocket to practical use it is slipped into the ordinary 60 knitted pocket of a billiard or pool table, with its open front toward the entrance to the pocket proper, and with the ends of its fingers B fastened to the edge of the table by tacks or otherwise, and flush, or nearly so, with the table-top, and the upper end of the extended rear portion, C, projecting up sufficiently high to receive the impact of a ball when driven into the pocket.

It will be apparent that a knitted pocket 70 provided with my invention will be completely protected from wear by the balls, and will last as long as any other part of the table.

Instead of constructing the supplemental pocket of leather, it may be made of rubber, 75 paper, vulcanized fiber, felt, or other suitable equivalent material.

Having thus described my invention, I claim as new—

1. A supplemental pocket for billiard or 80 pool tables, adapted to be slipped into the ordinary knitted pocket, consisting of a body of leather or like material, having its upper portion cut away at the front to admit the ball, and its upper back portion extended up so as to receive the impact of the ball, substantially as described.

2. The herein-described supplemental pocket, consisting of the body of leather or like material, having the open front, the flexible flaring fingers, and the extended back, as set forth. 90

FREDERICK KIEKENAPP.
